FIG. 3.

UNITED STATES PATENT OFFICE

PETER TAURISANO, OF SPRINGFIELD, MASSACHUSETTS

APPARATUS FOR INTERNAL-COMBUSTION ENGINES

Application filed August 2, 1929. Serial No. 383,027.

This invention relates to improvements in internal combustion apparatus and is directed particularly to carburetors or apparatus for supplying internal engines with fuel.

The principal objects of the invention are to provide an apparatus for mixing air and fuel such as gasoline in desired proportions and for delivering the mixture under more or less pressure to an internal combustion engine. By means of the apparatus the fuel and air are mixed in such proportions as will not only result in efficiency of operation of an internal combustion engine but will effect a saving in fuel.

These and numerous other objects and advantages are attained by means of the novel apparatus, the combination and arrangement of parts constituting the invention and which will be described in connection with the accompanying drawings, in which

Fig. 1 is a plan view of an apparatus embodying the novel features of the invention.

Fig. 2 is a side elevational view of the same with the parts broken away for clearness.

Fig. 3 is a sectional elevational view through the mixing chamber of the apparatus taken on the line 3—3 of Fig. 1.

Fig. 4 is a sectional plan view through the mixing chamber taken on the line 4—4 of Fig. 3.

Fig. 5 is a sectional elevational view through one of the cylinder head assemblies for one of the gasoline cylinders taken on the line 5—5 of Fig. 1, and

Fig. 6 is a similar view through one of the air inlet valves for an air cylinder taken on the line 6—6 of Fig. 1.

Referring to the drawings in detail the novel features of the invention will be described in the form at present preferred. It will be understood that various changes may be made in the form thereof without departing from the spirit and scope of the invention, therefore I do not wish to be limited to the exact form shown and described.

A block or support is represented at 2 which has a plurality of bores 4 therein which I shall refer to as cylinders. I pre-

fer to employ four of these cylinders although more or less may be used. Two of these may be called gasoline cylinders and the other two air cylinders, the former of which are closed at the upper ends by head members 6, while the latter are closed by head members 8. One air and one gasoline cylinder may constitute a pair, therefore in the form of the invention shown and to be described there are two pairs.

A crank case 10 is suitably fixed to and suspended from the lower side of the block and has rotatable therein a crank shaft 12. The joint between the case and block is of course preferably oil tight so that the shaft may rotate in a bath of oil carried in the case. Suitable filling and drainage openings although not shown may be provided in or associated with the block and case.

The crank shaft is provided with four offsets such as 14 and 16, one for each of the cylinders. Connecting rods 20 rotatable on the offsets of the shaft are suitably connected at their upper ends to pistons such as 22 shown at the right in Fig. 2. The offsets are arranged so that the pistons in the air cylinders are making a downward or suction stroke while the others are making an upward or discharge stroke, or vice versa.

A gear 178 is carried on the outer end of 80 the crank shaft whereby the apparatus may be driven by a chain or gear of an internal combustion engine or the like, and the opposite end of the shaft may extend outwardly so as to be used as a driver or be connected 85 to various other apparatus.

The heads 6 and 8 for closing the air and gasoline cylinders contain certain valves for admitting air and gasoline to their respective cylinders and will now be described with particular reference to Figs. 5 and 6. The construction of one of the heads 6 for the gasoline cylinders will first be described. The head members 6 are in screw threaded relation with the block at the upper side of the gasoline cylinders so as to close the cylinder. It has in slidable relation therein an inlet valve 30, a discharge valve 32 and a secondary discharge valve 34. The inlet valve 30 seats against the lower side of the head and is 100

urged into seating relation by a spring 36 disposed between a washer 38 carried on a stem 35 thereof and the bottom wall 40 of a recess 42 in the upper side of the head. A 5 cap 44 in screw threaded relation with the upper side of the head is arranged to receive an end of a gasoline supply pipe 46.

The discharge valve 32 is guided in the head 6 by a stem 33 and a spring 48 is disposed between the upper side of the valve and a cap 50 so as to urge the valve into the seating position shown. The cap is adapted to receive an end of a discharge pipe 52.

The valve 34 is similarly guided in the head by a stem 35 and is urged into seating position by means of a spring 54 disposed between the upper side of the valve and a cap 56 screw threaded in the head.

A passage-way 60 connecting a chamber 29, 58 above the valve 34 and the recess 42 is provided for the purpose now to be described.

As a so-called fuel-piston in the cylinder below the head descends so as to create suction the valve 30 is opened so as to admit fuel from pipe 46 into the cylinder. When the piston moves upwardly gasoline is forced outwardly past the valve 32 into the discharge pipe 52. Preferably the spring 48 is relatively weaker than the spring 54 for this reason. In the normal operation of the fuel piston the valve 32 will be the first to open, the spring 48 being weaker. As the piston delivers more gasoline than is needed in the pipe 52 so that more or less pressure is built 35 up in the line and in the cylinder fuel will tend to open valve 34 against its stiffer spring. As this valve 34 is opened fuel will flow therewith through passageway 60 and past inlet valve 30 and into the cylinder. In 40 reality the fuel discharged into pipe 52 depends more or less upon pressure conditions so that no more gasoline is delivered to the mixing chamber later to be described than is required.

45 The heads 8 over the air cylinders are somewhat similar to those over the gasoline cylinders except that two valves only are used. One of these is an inlet valve 70 and is shown in Fig. 6. This valve 70 has its stem 50, 72 guided in the head 8 and is urged into seating position by a spring 74 disposed between a lower wall 76 of a recess 78 in head 8 and the lower side of a cap 80. The cap 80 has in screw threaded engagement therewith 55 a hollow member 82 provided with a conical lower end for bearing on a similarly formed seat. An opening or openings 84 in the lower conical end of member 82 permits air, when the member is moved from its seats, to pass therethrough and through an opening 88 in the cap. By moving the member 82 up or down the amount of air admitted to valve 70 may be varied so that the air-piston below head 8 may deliver such various amounts of 60 air as may be required.

In each case the valve stems are arranged to permit the passage of air or fuel past the valve when the valves are open.

A cap 90 in the upper side of head 8 and similar to cap 50 in head 6 is disposed above a discharge valve (not shown) which is similar to valve 32. 70

By means of the head and valve construction shown air is drawn into the air cylinder by a downward movement of a piston and discharged by an upward movement into an 75 air discharge pipe 92.

Head and valve construction for one only of the air and gasoline cylinders have been described, but it will be understood that both the heads 6 are alike in construction as well 80 as are the heads 8.

The mixing chamber which receives the fuel and air delivered to the pipes 52 and 92 will now be described with particular reference to Figs. 3 and 4. 85

Mixing chambers 100 identical in construction are preferably in the form of cylinders and are disposed at one side of the block 2. These cylinders are closed at their lower ends by caps 102 in screw threaded engagement therewith and a plate 104 intermediate the upper and lower ends thereof are fixed thereto so as to provide an air chamber A therebelow and a mixing chamber M thereabove. 95

The air pipes 92 from the air cylinders previously described are connected to these chambers A so that air is delivered thereto by the air pistons. The plate 104 is provided with a plurality of perforations 106 therethrough and has fixed therein a central member 108. This member 108 has an axial bore 110 therein, and radial bores 112 in communication therewith which are in turn in communication with an annular groove 114 in the plate. A passageway 116 extends through the plate and wall of the chamber and receives a fitting 118 to which the gasoline pipe is connected. 110

With the arrangement described fuel such as gasoline is delivered to and through the bores 116, 112 and 110. A head member 126 in screw threaded engagement with the upper side of the chamber has a lower flange 128 so as to provide a secondary mixing chamber M'. A conical shaped projection 130 extends downwardly from the flange. A needle valve 132 threaded in the member 126 has a tapering lower end for seating in the periphery of the bore 110 in the member 108. By turning the valve 132 in one direction or the other it is moved up or down whereby the flow of fuel through the bore 110 is controlled or regulated. 120

A connection 136 in the member 126 receives a discharge pipe 158 so that it is in communication with the chamber M'. 125

The flange 128 and conical projection are provided with a plurality of openings 140. 130

A knurled knob 142 at the upper end of valve 132 carries an index pointer 144 which may be used for registering with graduations 146 in the upper side of cap 126 for setting the valve as may be desired.

At one side of the block 2 there is provided a longitudinal bore 150 in which is supported one or more tubes or pipes 152. Fittings 154 threaded in an end wall 156 of said bore support said tubes and receive the ends of the pipes 158 which extend from the mixing chambers so that mixed air and fuel under pressure is conducted from the mixing chambers to the tubes 152. These tubes are perforated as at 160 on their outer ends.

A discharge pipe 162 is connected to the block so as to receive the air and fuel mixture and may be arranged to conduct the mixture to the intake of an internal combustion engine. If desired a number of separate conduits may be connected to an equal number of openings 164 in the pipe 162 so that several separate pipes may extend to several separate cylinders of an engine.

In order to allow air to enter chamber 150 and mix with the mixture there is provided a plurality of openings 170 extending into the chamber. A plate 172 pivoted at 174 and provided with portions 176 for overlying said openings is rotatable by means of a handle 178 so that a flow of air into the chamber may be controlled. These openings will be utilized when the engine to which the pipe 162 is connected provides suction sufficient to cause air to enter therethrough.

The operation of the apparatus is as follows:—Ordinarily the apparatus will be used for supplying a mixture of air and fuel such as gasoline to an internal combustion engine and may be connected to and operated thereby. The fuel inlet valves 30 will be connected by means of the pipes 46 to a fuel supply tank. As the crank shaft of the apparatus rotates fuel is drawn in through valves 30 while air is drawn in through valves 70 by the fuel and air pistons respectively. The fuel and air are discharged through their respective valves and delivered through the pipes 52 and 92 to the mixing chambers at more or less pressure by reason of the pumping action of the pistons. Air enters the air chamber A of the mixing chamber and passes upwardly through plate 104 into mixing chamber M. Fuel enters the mixing chamber M past the end of valve 132 and through opening 110.

The air enters the mixing chamber M in relatively small streams while the fuel is sprayed more or less into the chamber so that the fuel and air are mixed. From the mixing chamber M the mixture of air and fuel passes upwardly through member 128 into the chamber M' and from there outwardly through the pipe 158 to the chamber 150.

The passage of the mixture through the openings in member 128 causes the fuel and air to become thoroughly mixed so that a relatively dry mixture is discharged into the chamber 150.

The amount of air admitted to the air cylinders may be varied by adjusting valves 82, while the amount of fuel delivered to the mixing chambers may be varied by adjusting valves 132. Also the tension of the springs for the various valves may be varied so that with various relative amounts of air and gas various desired pressure conditions may prevail.

By means of the apparatus it is possible to supply a fuel mixture to internal combustion engines which may be proportioned as to relative amounts of fuel and air, as may be required for various engines. At the same time the mixture may be delivered under pressure so that with the desired mixture and pressure efficiency and economy in operation may result.

Having described the invention in the form at present preferred, I now desire to claim:

1. An apparatus of the class described comprising in combination, a block provided with air and fuel cylinder bores, pistons in said cylinders, separate heads for said cylinders, the head for said air cylinder being provided with inlet and discharge valves, the head for said fuel cylinder being provided with an inlet, a discharge and a secondary discharge valve which is connected to said inlet valve for discharging thereinto.

2. An apparatus of the class described comprising in combination, a block provided with air and fuel cylinder bores, pistons in said cylinders, separate heads for said cylinders, the head for said air cylinder being provided with inlet and discharge valves, the head for said fuel cylinder being provided with an inlet, a discharge and a secondary discharge valve which is connected to said inlet valve for discharging thereinto, a mixing chamber and separate connections from said discharge valves thereto.

3. An apparatus of the class described comprising in combination, a block provided with air and fuel cylinder bores, pistons in said cylinders, separate heads for said cylinders, the head for said air cylinder being provided with inlet and discharge valves, the head for said fuel cylinder being provided with an inlet, a discharge and a secondary discharge valve which is connected to said inlet valve for discharging thereinto, a mixing chamber and separate connections from said discharge valves thereto, and a chamber connected to said mixing chamber for receiving mixed fuel and air therefrom.

4. An apparatus of the class described comprising in combination, a block provided with air and fuel cylinder bores, pistons on

said cylinders, a mixing chamber including separate mixing and air chambers and a fuel orifice which is in communication with the former and an air orifice in communication with the latter, separate connections between said air and fuel cylinders and said air and fuel orifices whereby fuel and air are delivered thereto.

5. An apparatus of the class described comprising in combination, a block provided with air and fuel cylinder bores, pistons in said cylinders, a mixing chamber including separate mixing and air chambers and a fuel orifice which is in communication with the former and an air orifice in communication with the latter, separate connections between said air and fuel cylinders and said air and fuel orifices whereby fuel and air are delivered thereto, and a receiving chamber for receiving mixed air and gas from said mixing chamber.

6. An apparatus of the class described comprising in combination, a block provided with air and fuel cylinder bores, pistons in said cylinders, a mixing chamber including separate mixing and air chambers and a fuel orifice which is in communication with the former and an air orifice in communication with the latter, separate connections between said air and fuel cylinders and said air and fuel orifices whereby fuel and air are delivered thereto, and a receiving chamber for receiving mixed air and gas from said mixing chamber and means for admitting air to said receiving chamber.

7. An apparatus of the class described comprising in combination, a block provided with separate air and fuel cylinders with pistons thereon, a mixing chamber including air and mixing chambers separated by a partition, a pipe connection between said air cylinder and said air chamber and the said partition being perforated to permit the passage of air into said mixing chamber and a connection between said fuel cylinder and mixing chamber.

8. An apparatus of the class described comprising in combination, a mixing chamber including a lower air chamber, an intermediate mixing chamber and an upper secondary mixing chamber which are separated by perforated partitions, a gas cylinder and an air cylinder in communication with said mixing and air chambers respectively and an outlet in communication with the secondary mixing chamber.

9. An apparatus of the class described comprising in combination, a closed air cylinder and a fuel chamber having pistons therein, a mixing chamber having a lower air chamber, an intermediate mixing chamber and a secondary mixing chamber which are separated by perforated partitions, heads on said cylinders having inlet and discharge valves, the discharge valves in said heads

being connected to the air chamber and mixing chamber respectively and means associated with said partitions for controlling the passage of fuel into said chamber.

10. An apparatus of the class described comprising in combination, a support having an air cylinder, a fuel cylinder and a bore therein, pistons in said cylinders, heads closing the upper sides of said cylinders provided with inlet and discharge valves, a mixing chamber having an air chamber and a mixing chamber separated by a perforated wall, connections between the discharge valves and said air and mixing chambers, a pipe in said bore and a connection between said mixing chamber and said pipe.

In testimony whereof I affix my signature.

PETER TAURISANO.
